UNITED STATES PATENT OFFICE.

ETTORE VIANI, OF MILAN, ITALY.

IGNITION-MAGNETO FOR INTERNAL-COMBUSTION ENGINES.

1,366,222.

Specification of Letters Patent. Patented Jan. 18, 1921.

Application filed August 19, 1919. Serial No. 318,523.

To all whom it may concern:

Be it known that I, ETTORE VIANI, a subject of the King of Italy, resident of Milan, Italy, 3 Via Castelvetro, in the Kingdom of Italy, have invented new and useful Improvements in Ignition-Magneton for Internal-Combustion Engines, of which the following is a specification.

The invention relates to an improvement 10 in internal combustion engine magnetos, by means of which the timing of the ignition can be conveniently adjusted and the make-and-break device can be readily taken off for inspection and cleaning of the contacts.

One method of carrying the invention 15 into effect is illustrated by way of example in the annexed drawing, in which:

Figure 1 shows the magneto in longitudinal section;

Fig. 2 is a cross section through 2-2 in Fig. 1;

Fig. 3 is a cross section through 3-3 in Fig. 1;

Fig. 4 shows the locking device for the 25 revolving iron shield.

In the casing S, inside of which project the pole-shoes R of the magnets M, is arranged the iron shield B which can be rotated about a desired angle according to the 30 timing conditions and consists of two cast iron segments that are held together by two brass end rings T-U whose external diameter is equal to the internal diameter of the casing, the rings thus suiting the casing. 35 Within the shield B revolves the armature E.

The front ring T carries the revolving locking arrangement A, which actuates a spring-loaded bolt K (Figs. 3 and 4). The 40 bolt K can lock the make-and-break C in a corresponding recess C' of the ring T or release it therefrom, and this arrangement permits of the make-and-break device being readily taken out for inspection and cleaning of the contacts. In order to replace it 45 into position the make-and-break device is first put in place laterally, as shown in dotted lines by Fig. 3, in such a way that its lower end embraces a pin J and can pivot thereon; after this, by giving it a stroke 50 with the thumb, the whole is caused to pivot about the pin J until the hole Q is brought exactly opposite the bolt K. The beveled end-surface of the spring loaded bolt K 55 permits of the bolt sliding backward, thus permitting the piece C to enter the recess C';

then due to the action of the spring the bolt K is forced into the hole Q, thereby making the make-and-break C fast with the ring.

D is one of the contacting members and 60 it comprises the platinum-plated screw and a carbon-brush bearing through a hole N in the ring T on the slip ring fixed to the armature E. F is the other contacting member having the platinum-plated screw closing 65 the contact that is connected up to the body of the magneto and therewith to the primary winding; the contact of the screw F with the screw D, has the purpose of short circuiting the primary winding in the well 70 known manner. The rupture of the short circuit takes place when F, which is arranged at the end of a lever pivoting about O, is oscillated by a cam G made of insulating material and mounted on the armature 75 shaft at the opposite end P of the same lever.

The speed reduction for the distributor is obtained by means of a pinion L keyed on 80 the rotor shaft and meshing with the internal teeth of a circular rack I revolving in a ball-race bearing. In order to realize a smooth and noiseless running the pinion L and the internally toothed circular rack I are fitted with helical teeth; the circular 85 rack I is solid with the brush-holder V which makes the contacts on the distributor H secured to the casing.

Z is the crank-handle by means of which 90 the cast iron shields B are angularly adjusted in order to adjust the timing of the ignition in a manner well known.

Of course the constructional details and the particulars relating to the form of the various parts may be varied from those 95 shown and illustrated without departing from the spirit and scope of the invention.

Having now particularly described and ascertained the nature of my said invention and in what manner the same is to 100 be performed, I declare that what I claim is:

An ignition magneto for internal combustion engines, comprising an armature shaft, brass rings coaxial therewith and connecting the ends of segment-shaped cast iron shields for varying the timing of the ignition, one of said rings having an opening therein, a make-and-break device locked in said opening by a spring-loaded bolt when 105 the make-and-break device is in operation, said bolt being beveled so as to move auto-

matically backward while inserting or taking off the make-and-break device, a cam on the armature shaft acting on the make-and-break device through the opening in the ring, a pinion having helical teeth keyed on the armature shaft, a casing, a distributor secured to said casing, a brush holder for making contact with said distributor, and an internally toothed circular rack run-

ning in a ball-race bearing in said casing 10 and solid with the brush holder of the distributor and coöperating with said pinion.

In testimony whereof I affix my signature.

ETTORE VIANI.
